UNITED STATES PATENT OFFICE.

SIMON FAIRMAN, OF BALTIMORE, MARYLAND, ASSIGNOR OF ONE-HALF TO
JOHN G. MITCHELL AND WILLIAM S. TAYLOR, BOTH OF SAME PLACE.

CAR-BRAKE.

SPECIFICATION forming part of Letters Patent No. 291,841, dated January 8, 1884.

Application filed September 21, 1883. (No model.)

To all whom it may concern:

Be it known that I, SIMON FAIRMAN, of the city of Baltimore, and State of Maryland, have invented certain Improvements in Car-Brakes, 5 of which the following is a specification.

This invention relates to a car-brake in which the brake mechanism is actuated primarily by checking the speed of the locomotive and tender, and the consequent pressure of one car 10 against another as they are successively checked. In other words, the speed of the engine and tender being reduced by the reversal of the driving-wheels or by other means, the first or adjoining car, in view of its momentum, is 15 forced against the tender and its brake mechanism put in operation. The checking of this car causes the second one to advance upon the first, when its brake mechanism is automatically actuated, and so on until the brakes on 20 the whole train are applied.

In the accompanying drawings, forming a part hereof, Figure I is a side view of a portion of a train provided with my improved brake mechanism. Figs. II, III, IV, V, VI, 25 and VII are views of parts of the invention on an enlarged scale.

Similar letters of reference indicate similar parts in all the views.

Referring particularly to Figs. II, III, IV, 30 V, and VI, which show one end only of a car, A is the frame-work of the car, and B the swivel-bolt around which the truck C moves when the train is rounding a curve. D and E are respectively the wheels and the axles.

35 F is the coupling, and G the draw-bar, which extends from the coupling and bears against a spring, (not shown in the drawings,) which serves to retain the coupling yieldingly in an extended position when the car is separated from another.

H is a lever having its fulcrum at a in the stand b, which stand is bolted to the under side of the frame A of the car.

I is a double swinging arm, pivoted at c to 45 the frame A of the car, having at its lower end a roller, d, which rests on the upper surface of the lever H. The draw-bar G, which passes between the two parts of the swinging arm I, has a pin, e, whose ends enter a slot, f, 50 in the arm I, and when the draw-bar and coupling are extended, as shown in Figs. I and III,

the said arm hangs in a vertical position, with its roller d in a depression, g, in the outer end of the lever H. The inner end of the lever H is forked and provided with inwardly-projecting legs h, which rest in a groove, i, in the collar k, which is adapted to slide vertically on the swivel-bolt B. 55

K is a shaft or spindle with one end pivoted to a block, L, fastened to the upper surface of 60 a bar, M, which is bolted to the truck of the car, and the other pivoted to a projected portion, l, of the collar k.

N is a worm-wheel adapted to revolve loosely on the spindle K, having teeth on a portion 65 only of its circumference, and O a worm keyed to the axle E.

P and Q are respectively a ratchet-wheel and a sheave, which are cast or attached together, and adapted to turn independently of 70 the spindle K, in the same manner as the worm-wheel N. A pawl, m, on the side of the worm-wheel N engages with the ratchet-wheel P, and the rotation of the said worm-wheel N in one direction is therefore communicated to 75 the said ratchet-wheel and its sheave. A chain, n, is secured to the sheave Q, and after passing around a small guiding-sheave, o, (shown in Figs. II, III, and VI,) is attached to the brake-lever p, which is of ordinary construction, and operates the brake-shoes q in 80 the usual manner.

Parts of the invention not yet alluded to will be described and their uses fully set forth in the description of the operation of the said 85 invention which follows. Supposing the train to be in motion, the draw-bars and couplings are all extended, and the arms I throughout the entire train in a vertical position, with their rollers d resting in the depressions g in 90 the levers H. The outer ends of the said levers are thus held in a depressed position, with their inner ends and the collars k elevated, and the worm-wheel N disengaged from the worm O, as shown in Figs. I and III. This 95 disengagement of the worm-wheel N from the worm O admits of the free revolution of the axles, and the braking mechanism is therefore rendered inoperative.

To apply the brake, the speed of the engine and tender is checked in any manner, when the couplings are forced in, which car- 100

ries the arms I to the second position, (shown particularly in Fig. II,) and the worm-wheels brought in contact with the revolving worms on the axles. The worm-wheels are thus put 5 in revolution, and the brake-levers h operated by the winding of the chains on the sheaves Q, which receive their movement from the worm-wheels, as before described.

To provide against the application of the 10 brakes in backing, I furnish each car with a rod, r, which extends its entire length and to the faces of the couplings, and has springs s to hold it in a central position, as shown in Figs. I and VII. These rods have bars R extending from them, as shown in the drawings, or they may be pivoted to the frame A and connected to the said rods by means of pins, in a manner similar to the connection between the draw-bars and the arms I. The 15 tender has also a rod, r, and a hand-lever, v, or other similar device, whereby the rod may be forced back and be brought in contact with or made to approach the rod on the first car. The rod on this car can thus be forced toward 20 the rod on the second car, and that of the second toward the third, and so on throughout the entire train.

When it is desired to back the train without applying the brake, the hand-lever v is 25 thrown forward, when the distance between the couplings is decreased and the ends of the rods r brought in contact, and the whole system driven back. In the movement of the rods r, the bars R are carried over the outer ends of 30 the levers H, which secure them in a depressed position, without reference to the position of the arms I.

In using the swivel-bolt B as the support and guide for the collar k the brake mechanism is not interfered with or dislocated in 35 rounding curves.

It will be understood that the pressure obtained by the advance of one car on another which is checked in speed is not directly em-

ployed to effect the braking operation, but 45 merely to put in motion a system of devices which actuate the brake-shoes through the ordinary brake-levers.

By providing the worm-wheels N with teeth on a portion only of their circumference, the 50 tension placed upon the chains n is limited, and under no circumstances can they receive a strain greater than what is provided for in the adjustment of the brake.

I claim as my invention—

1. In a car-brake, the combination of a car-axle, a worm secured to the said axle, an independent shaft carrying a worm-wheel and susceptible of being moved toward and from the worm, a sheave on the independent shaft, 60 a chain to connect the said sheave with the ordinary brake mechanism, a longitudinally-moving draw-bar, and means to communicate movement from the said draw-bar to the said independent shaft and its attachments, substantially as specified.

2. In a car-brake, the combination of a car-axle, a worm secured to the said axle, an independent shaft carrying a worm-wheel with teeth on a portion only of its circumference, 70 and adapted to have movement toward and from the said worm, a sheave on the said independent shaft, a chain to connect the said sheave with the ordinary brake mechanism, a longitudinally-moving draw-bar, and means 75 to communicate movement from the said draw-bar to the said independent shaft and its attachments, substantially as specified.

3. The vibratory shaft K, carrying the worm-wheel N, pivoted to a part of the collar k on the swivel-bolt B, combined with mechanism which receives its movement from the longitudinal motion of the draw-bar, substantially as specified.

SIMON FAIRMAN.
